Primary Examiner — Dominic V Simone*(74) Attorney, Agent, or Firm* — Banner & Witcoff, Ltd.**CLAIM**

The ornamental design for a shoe upper, as shown and described.

DESCRIPTION

FIG. 1 is a front perspective view of a shoe upper showing my new design;

FIG. 2 is a side view thereof;

FIG. 3 is an opposite side view thereof;

FIG. 4 is a front view thereof;

FIG. 5 is a rear view thereof; and,

FIG. 6 is a top view thereof.

The uneven-length broken line immediately adjacent to the bottom of the shaded area defines the bounds of the claimed design and forms no part thereof. The even-length broken lines within the shaded area represent stitching which forms no part of the claimed design. The uneven-length broken lines showing of the circular perforations, the lace holding elements, and the remainder of the shoe represents unclaimed subject matter and forms no part of the claimed design.
